UNITED STATES PATENT OFFICE

2,546,037

PRY TYPE VACUUM CAP REMOVER

Joseph J. McGuinness, Waterbury, Conn., assignor to John M. Freiheit, Waterbury, Conn.

Application June 19, 1947, Serial No. 755,557

5 Claims. (Cl. 81—3.36)

1

This invention relates to cap removers, and more particularly to a device for opening receptacles of the type having a "vacuum" cap which must be pried therefrom, said receptacle and cap providing slightly separated exterior shoulders which will admit a thin prying tool therebetween.

One object of this invention is to provide a device of the above nature which includes means for locating and firmly holding the device manually against the receptacle in proper position for the efficient operation of the prying cam.

Another object is to provide a device of the above nature which will require no clamps, encircling bands, or other means for securing the device to the receptacle.

Another object is to provide a device of the above nature having a prying cam which is readily adjustable with relation to the locating means, whereby the device will operate efficiently to open receptacles of a wide range of sizes.

A further object is to provide a device of the above nature which will be simple in construction, inexpensive to manufacture, easy to apply and manipulate, compact, ornamental in appearance, and very efficient and durable in use.

With these and other objects in view, there has been illustrated on the accompanying drawing one form in which the invention may conveniently be embodied in practice.

In the drawings,

Fig. 1 is an oblique elevational view, showing the front and side of the improved pry-off cap remover.

Fig. 2 is a cross section on the line 2—2 of Fig. 1, looking downwardly.

Fig. 3 is a plan view showing the flattened cam and a portion of the bit.

Fig. 4 is an elevation showing the cap remover as it appears in the operation of removing a cap from a receptacle.

Referring now to the drawings in which like reference numerals denote corresponding parts throughout the several views, the numeral 10 indicates an elongated vertical channel-shaped frame formed from sheet metal and comprising a pair of divergent wings 11, 12 extending integrally from opposite edges of a rectangular back 13.

The upper end of the back 13 is extended above the wings 11, 12 and then rearwardly and downwardly to form an inverted U-shaped lug 14. A bit 15 in the form of a cylindrical rod is slidably and rotatably supported in a pair of aligned apertures 16 formed in the sides of the U-shaped lug 14, and retained therein by a flat key 17, secured,

2

as by welding, to the rear end of the bit 15—said bit having a wide flattened forward cam 18 formed integrally with the front end thereof, which also assists in keeping the parts from separation.

The aligned apertures 16 in the lug 14 are so disposed as to hold the bit 15 slidably in a position bisecting the angle between the divergent wings 11, 12. The flattened cam 18 may be made of any suitable proportions to fit under any "pry-off" cover cap commonly found on the market. In one instance it has been found that a cam three-eighths of an inch wide, and one-sixteenth of an inch thick will operate satisfactorily over a wide range of bottle sizes.

Operation

In operation, the centralizing frame 10 will be held manually in a vertical position against the side of the receptacle R which it is desired to open, in the position shown in Fig. 4. The divergent wings 11, 12 will then serve to locate the frame 10 upon the side of a cylindrical or polygonal receptacle in a position substantially parallel to its axis.

The cam 18 will be then inserted into the narrow space between a shou'der 19 of the receptacle R and a projecting edge 20 of the cap C, by a sliding movement of the bit 15 in the lug 14—the extent of said movement being dependent upon the relative diameter of the receptacle and the edge of the cap.

While the frame 10 is held against the receptacle R by one hand, the key 17 will be rotated by the other hand to turn the cam 18. The cam 18 will thus relieve the vacuum in the receptacle and effectively pry the cap therefrom—the parts then assuming the position shown in dotted lines in Fig. 4, wherein the numeral 18' indicates the position of the cam, the numeral 19' indicates the position of the receptacle shoulder, and the numeral 20' indicates the position of the projecting edge of the cap C.

The width of the cam 18 preferably is such that when it is disposed vertically, as shown in dotted lines in Fig. 4, the cap C will be raised to a position where it may be readily lifted from the receptacle R, and yet not raised sufficiently to permit said cap to slide accidentally off of said receptacle.

One advantage of the improved pry-off vacuum cap remover herein disclosed is that it will operate efficiently to remove caps of various sizes from receptacles of different diameters.

Another advantage is that it is not necessary

to clamp the device upon the receptacle as it may be held in its operative position with one hand while the cam is operated with the other hand.

A further advantage is that the bit 15 is slideable so that application of the device may easily be made, inasmuch as the frame 18 may be applied against the side of the receptacle while the cam is in retracted position, and the cam 18 then inserted into the narrow space between the shoulder 19 and the projecting edge 20 of the cap C.

Another advantage is that the device is small, light in weight, and may be readily manufactured without requiring any complicated forming operations or tools.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a cap remover for cylindrical containers of the type providing a narrow space between a shoulder on the container and the edge of its cap, a channel-shaped frame having spaced vertically extending edges for engagement with the side of the vertically-held container, a cam mounted in said frame for rotation about an axis perpendicular to said edges, and a handle for rotating said cam, said handle including a bit slideable horizontally in said frame and carrying said cam.

2. The invention as defined in claim 1, in which said frame includes an upper outwardly-

offset extension of inverted U-shape provided with aligned apertures slidably and rotatably supporting said bit.

3. A cap remover for cylindrical containers of the type providing a narrow space between a shoulder on the container and the edge of its cap, an elongated vertically extending channel-shaped centralizing frame, a horizontal bit, said frame having an aperture in the web portion thereof for rotatably and slidably supporting said bit at right angles to said web portion in substantially equidistant relation to the vertical side edges of said frame, said bit including a flat end cam located on the concave side of said frame, and manual operating means at the other side of said frame.

4. The invention as defined in claim 3, in which said bit is slideable in said aperture, and said cam and said operating means are laterally enlarged whereby said bit will be retained in said aperture.

5. The invention as defined in claim 3, in which the back of said frame is extended rearwardly and downwardly, and provided with an additional bit-supporting aperture aligned with the aforesaid aperture.

JOSEPH J. McGUINNESS.
